STENOGRAPHIC MACHINE

Victor Charles Dold, Issy-les-Moulineaux, France,
assignor to Le Progres Technique, Paris, France,
a corporation of France

Application December 27, 1938, Serial No. 247,922
In France December 30, 1937

4 Claims. (Cl. 197—164)

This invention relates to stenographic machines of the type in which the platen does not partake of longitudinal movement, but is rotated through a small angle upon the completion of each printing operation, so that successively printed letters, symbols or the like, or groups of letters, symbols or the like, occupy successive lines on a web or sheet advanced by rotation of the platen.

One special object of the invention is to provide, in a stenographic machine of the type mentioned, simple, practicable, reliable means whereby successive steps of advance of the platen are effected steadily and quietly and particularly in definite, invariable amounts so that successively printed lines are evenly spaced apart.

Another special object of the invention is to provide, in a machine of the type mentioned, simple, practical, reliable means for effecting step by step rotation of the reels carrying an inking ribbon, so that said ribbon is advanced step by step during operation of the machine, and for automatically reversing the direction of rotation of said reels at predetermined times so that the inking ribbon is wound first onto one and then onto the other of said reels.

With the foregoing and other objects in view, which will become more fully apparent as the nature of the invention is better understood, the same consists in the novel features of construction, combination and arrangement of parts as will be hereinafter more fully described, illustrated in the accompanying drawings and defined in the appended claims.

In the accompanying drawings, wherein like characters of reference denote corresponding parts in the different views:

Fig. 1 is a top plan view of a stenographic machine embodying the features of the invention.

Fig. 2 is a longitudinal section on the line 2—2 of Fig. 1.

Fig. 3 is a side-elevation of the machine.

Fig. 4 is a detail transverse view showing particularly the gearing for rotating one of the reels carrying the inking ribbon.

Figs. 5 and 6 are elevations of parts of the mechanism for reversing the direction of feed of the inking ribbon.

Figs. 7 and 8 are sectional views showing the friction clutches at the ends of the platen controlling rotation of the platen; and

Fig. 9 is a detail view illustrating the relationship to each other of certain of the hammers carrying the characters to be printed.

Referring to the drawings in detail, 1a, 1b

designate a pair of side-plates, which constitute main frame elements of the machine and which are understood to be rigidly connected together in spaced apart relationship by suitable cross-members.

Between the side-plates 1a, 1b is a horizontally disposed platen 2, which extends transversely of the machine and which includes shaft elements 53 projecting beyond its ends and journaled in the side-plates 1a, 1b whereby the platen is 10 mounted for rotation.

In front of the platen 2 is a horizontal shaft 15, which extends transversely of the machine and is rockably mounted at its ends in the side-plates 1a, 1b and which has rockably mounted 15 thereon in side to side relationship a plurality of hammers 3 and 3c for cooperation with said platen 2.

Each hammer 3 and 3c includes an arm 3a extending upwardly from the shaft 15 and having a rearwardly directed terminal portion 3b provided with a printing character in the form of a letter, group of letters, symbol or the like, an arm 9 extending forwardly from the shaft 15 and an arm 10 extending downwardly from said shaft.

Below and in front of the shaft 15 is a cross-bar 6 having therein a series of slots which open through the top thereof and which accommodate intermediate portions of a series of key levers 5, 30 one related to each hammer 3 and 3c. The key levers 5 are rockably mounted on fulcrums at the bottoms of the slots in the bar 6 and each key lever is operatively connected with the arm 9 of its related hammer 3 or 3c by a rod 7 slidable 35 in an opening in a cross bar 8 mounted at its ends in the side plates 1a, 1b. Carried by each key lever at its forward end is a key 4 for finger depression to rock the key lever, while associated with the hammers 3 and 3c are individual springs 40 11, which tend constantly to rotate said hammers in directions to swing their upwardly extending, printing character carrying arms forwardly with respect to or away from the platen 2. Thus, whenever any given key lever 5 is rocked by depression of its key 4, the related hammer 3 or 3c is rocked in a direction to cause its printing character to cooperate with the platen 2, and whenever any key lever, after being rocked, is released, the spring 11 returns the related hammer 3 or 3c to its normal position in which its printing character is spaced forwardly of the platen 2. Any suitable stop means may be provided to determine the normal positions of the hammers 3 and 3c, and the springs 11 may be of any suit- 55

able type. As illustrated in the present instance, the springs 11 are of the leaf type, each being secured at one end to a rotatably adjustable cross-shaft 12 and each bearing at its other or free end against the arm 10 of its related hammer 3 or 3c. Obviously, by rotatably adjusting the shaft 12 the force exerted by the springs 11 on the hammers 3 and 3c may be regulated. On the shaft 12 is a ratchet wheel 13 with which operates a suitable pawl 14 whereby said shaft may be held in different rotatably adjusted positions.

Fixed, respectively, to opposite end portions of the shaft 15 are two levers 16 of inverted L-shape, each including an arm 16a extending forwardly from said shaft and an arm 18 extending downwardly therefrom. Connecting the arms 16a of said levers and disposed in overlying relationship to the arms 9 of the hammers 3 and 3c is a plate 17 having on its under side a suitable pad 17a for noiseless contact with said arms 9. Extending upwardly from said levers are arms 19 with which cooperate springs 20 which tend constantly to rotate said levers in directions to swing their arms 16a downwardly and their arms 18 rearwardly. Thus, the plate 17 normally is urged downwardly with its pad 17a engaged with the arms 9. Accordingly, when any hammer 3 or 3c is rocked by actuation of its related key lever 5, the plate 17 is elevated and the arms 18 of the levers 16 are swung rearwardly, while upon return of any rocked hammer 3 or 3c to its normal position the springs 20 serve to return the levers 16 to their normal positions.

Disposed at one side of the machine behind one of the levers 16 and below the platen 2 is a substantially vertically disposed lever 22, which is pivoted intermediate its ends to the adjacent side plate 1b, as indicated at 23, and which is connected at its lower end with the lower end of the arm 18 of the related lever 16 by a link 21. Similarly disposed at the other side of the machine and similarly connected with the other lever 16 is a second lever 22a, which may be a duplicate of the first mentioned lever 22, but which, instead of including an arm extending above its pivot 23 as in the case of said first mentioned lever 22, preferably is devoid of such an arm. In any event, whenever the levers 16 are rocked as a result of rocking of any hammer 3 or 3c by actuation of its related key lever 5, the levers 22, 22a are rocked due to their connections with the arms 18 of said levers 16.

In the upper arm of the lever 22 is a slot 24 in which is disposed a pin 26 carried by a lever arm 25 which is rotatably mounted on one of the shaft elements 53 of the platen 2 and which is suitably held against outward movement along said shaft element relative to the adjacent end of said platen.

Between the lever arm 25 and the adjacent end of the platen 2 is a coil spring 58 which is fastened at one end to said lever arm 25 and which bears frictionally at its other end against the adjacent end of the platen 2. Thus, whenever the lever 22 is rocked, the lever arm 25 is rocked and, due to the friction clutch afforded by the spring 58 between said lever arm 25 and the platen 2, the latter is rotated. In this connection it is pointed out that the length of the arms of the levers 16, 22 and 25 is such that upon actuation of any hammer 3 or 3c the platen 2 is rotated through an angle corresponding to the spacing of successive lines to be printed on a sheet 75 or web 61 which is trained over the platen 2 and

which is advanced step by step with said platen as the latter is intermittently rotated by successive actuations of the hammers 3, 3c. It is also pointed out that the spring 58 is wound in a direction such that it does not serve to rotate the platen 2 when any given hammer 3 or 3c is rocked in a character printing direction, but does serve to rotate said platen when any given hammer 3 or 3c returns to its normal position after having effected printing. The spring 58 is wound about a drum 57 fixed with respect to the platen 2 and is covered by a sleeve 59 which may serve as a retainer for a suitable lubricant, such as graphite, for the spring 58.

Between the other end of the platen 2 and the adjacent side plate 1 is another coil spring 55 which is fixed at its outer end to said side plate and which bears at its inner end against the end of the platen. This spring 55 is wound oppositely with respect to the spring 58 and serves to hold the platen against retrograde rotation during swinging movement of the lever arm 25 as effected by depression of any key lever 5, yet does not interfere with rotation of said platen in a direction to advance the sheet or web 61. As in the case of the spring 58, the spring 55 is wound upon a drum 54 fixed with respect to the platen 2 and is covered by a lubricant retaining sleeve 56. The two springs 55, 58 obviously act to hold the platen against rotation except when it is advanced by actuation of the lever arm 25 and, moreover, serve as silent clutch means for effecting step by step advance of said platen.

Rearwardly of the platen 2, a pair of drum shafts 35b, 35b are rotatably mounted in the side plates 1a, 1b respectively, and carry, at the outer sides of said side plates, drums 35, 35a respectively, on which are wound the ends of an inking ribbon 60, which is suitably guided along the front of the platen 2 between said platen and the character carrying rearward extensions 3b of the arms 3a of the hammers 3, 3c, so that whenever any hammer 3 or 3c is rocked by actuation of its related key lever 5 its character is printed upon the sheet 61 disposed between the ribbon 60 and the platen 2.

Fixed on the drum shafts 35b, 35b are gear wheels 34, 34a, respectively, with which cooperate pinions 32, 32a, respectively, carried by arms 27, 27a, respectively, which are disposed substantially horizontally and which extend rearwardly from the levers 22, 22a, respectively, to which they are pivotally connected at their forward ends as indicated at 28 at points below the pivots 23 of said levers 22, 22a.

Each pinion 32, by a suitable pawl and ratchet or similar mechanism, designated generally as 33, is mounted on its related arm 27 for free rotation relative thereto in one direction and for non-rotation relative thereto in the opposite direction. The said directions of free rotation and non-rotation being such that said pinions rotate freely relative to the gear wheels 34 when either arm 27 is moved forwardly, and are non-rotatable in the opposite direction so that when either arm 27 is moved rearwardly and its pinion 32 is in mesh with the related gear wheel 34, rotation is imparted to such gear wheel in a direction to impart inking tape winding-on rotation to the related drum 35.

Below the arms 27, 27a are pivoted levers 30, 30, respectively, which carry rollers 29, 29, respectively, engaged with the under sides of said arms 27, 27a, respectively, and which are biased by suitable springs 31, 31, respectively, so that the

arms 27, 27a constantly are urged upwardly to mesh their pinions 32 with the gear wheels 34 and yet are capable of being swung downwardly to dispose the pinions 32 suitably below the gear 5 wheels 34 so that they do not cooperate with said gear wheels responsive to forward and rearward movements of the arms 27, 27a.

From the foregoing it will be apparent that upon depression of any key lever 5 the arms 27, 10 27a are moved forwardly and, upon release of the key lever, are moved rearwardly responsive to return of the levers 16 and 22 to their normal positions. Thus, if either of the arms 27, 27a is held in a lowered position and the other of said arms 15 is permitted to remain in an upper position, it is apparent that reciprocations of the first mentioned arm will not affect the related gear 34 and its drum 35, but that reciprocations of the other of said arms will result in step by step rotations 20 of the related gear wheel 34 and its drum 35 in a direction to effect winding of the inking ribbon 60 onto said drum.

On the shafts 35b, 35b are two-arm levers 36, 36a, respectively, which are operatively connected 25 to said shafts by suitable pawl and ratchet or equivalent mechanisms, designated as 62, so that rotation of either of said shafts 35b in an inking ribbon winding-on direction requires the related lever 36 to rotate therewith, and so that either shaft 35b may rotate in an opposite or inking ribbon unwinding direction even though its related lever 36 may be held against rotation in a corresponding direction.

A pair of stop pawls 39, 39a are provided for 35 cooperation with the levers 36, 36a, respectively, to predetermine normal or starting positions of said levers 36, 36a. Each stop pawl 39 is biased by a spring 40 to a position against a stop 41 in which the pawl serves as a stop engageable by a 40 pin 38 on one of the arms of the related lever 36 to prevent rotation of said lever when the related shaft is rotated in an inking ribbon unwinding direction. Thus, whenever either shaft 35b is 45 rotated in an inking ribbon unwinding direction, the related lever 36 assumes a predetermined starting position against its related pawl 39, as illustrated by dot and dash lines in Fig. 2 of the drawings, from which position it is advanced 50 when, subsequently, inking tape winding-on rotation is imparted to the related shaft 35b.

During inking ribbon winding-on rotation of either shaft 35b the related lever 36 of course rotates with said shaft and during such rotation its 55 pin 38 simply passes by the related pawl 39 which yields, as is apparent.

The other arms of the levers 36, 36a carry pins 37, 37a, respectively, for cooperation with gear-wheels 42, 42a, respectively, mounted on stub 60 shafts carried by the side plates 1a, 1b, respectively. During rotation of either lever 36 with its shaft 35b in an inking ribbon winding-on direction of rotation of said shaft, the pin 37 engages, once during each complete rotation of the lever 65 36, with the teeth of the related gear wheel 42 and imparts partial rotation thereto.

Fixed to the gear wheels 42, 42a are pinions 43, 43a, respectively, which mesh with gear wheels 44, 44a, respectively also mounted on stub 70 shafts carried by the side plates 1a, 1b, respectively. Fixed with respect to the gear wheels 44, 44a are pinions 45, 45a, respectively, which mesh with gear wheels 46, 46a, respectively, fixed to opposite end portions, respectively, of a cross-shaft 47. Thus, between each gear wheel and

the shaft 47 there is a reduced speed gear train so that a large number of revolutions of either of the levers 36 are required to effect 180° of rotation of the shaft 47.

On opposite end portions of the shaft 47 are 5 fixed cams 48, 48a, respectively, for cooperation with two-arm levers 49, 49a, respectively, rockably mounted on stub shafts carried by the side plates 1a, 1b, respectively.

One arm of each lever 49 or 49a carries a pin 10 or roller 50 or 50a for cooperation with its related cam 48 and the other arms of said levers 49, 49a carry pins or rollers 51, 51a, respectively, for co-operation with the arms 27, 27a, respectively.

The two-arm levers 49, 49a are disposed at the 15 outer sides of the plates 1a, 1b, respectively, and the pins or rollers 51, 51a of said levers extend through slots 52 in said side-plates to positions in overlying relationship to the arms 27, 27a, respectively.

The cams 48, 48a are of semi-circular shape and are disposed diametrically opposite each other. Moreover, the levers 49, 49a are disposed relative to said cams, respectively, and the arms of each lever are disposed relative to each other, so that when either cam 48 is in an upper position, as shown in Fig. 6, the related lever 49 is permitted to be swung upwardly by its associated elevating means 29, 30 and 31 to a position for cooperation of the pinion 32 of said arm 27 with the related gear wheel 34 responsive to reciprocation of said arm 27; also, so that when either cam 48 is in a lower position, as shown in Fig. 7, the related lever 49 is held in a position holding the related arm 27 depressed for non-cooperation of the related pinion 29 with the related gear wheel 34 responsive to reciprocation of said arm 27.

Assuming that one of the cams 48 is disposed 40 in an upper position permitting cooperation of the pinion 32 of the related arm 27 with the related gear wheel 34, and that the other of said cams 48 is disposed in a lower position holding the related arm 27 depressed and therefore preventing cooperation of the pinion 32 of said arm 45 with its related gear wheel 34, the operation of the machine is as follows: Upon depression of any key lever 5, the related hammer 3 or 3c is rocked and, acting through the ribbon 60, produces an impression of its character on the paper sheet 61. At the same time the plate 17 is rocked with the result that the lever arms 18 are swung 50 forwardly. This results in forward swinging movement of the lower portions of the levers 22 and in forward movements of the arms 27, 27a 55 and their pinions 32, 32a, respectively. Forward swinging of the lower end portion of the lever 22 that is related to the lever 25 results, of course, in rearward swinging of the upper end portion of 60 said lever and this, in turn, results, of course, in the lever 25 being swung rearwardly, without effect on the platen, as heretofore stated. Forward movement of the elevated arm 27 results simply in the pinion 32 of said arm idling over the related gear wheel 34, while forward movement of the arm 27, that is held depressed, is entirely idle movement. The depressed key lever 5 then is released, whereupon the springs 11 and 20 return the hammer 3 or 3c and the levers 16 and 22 to 70 their normal or starting positions. Accordingly, the lever 25 is swung forwardly advancing the platen 2 one step and the arms 27 are shifted rearwardly. Rearward shifting of the arm 27 that is held depressed is entirely idle movement, 75

but rearward shifting of the other of said arms 27 results in a step of rotation being imparted to the related gear wheel 34, due to the cooperation of the pinion 32 of such arm 27 with said related gear wheel 34. The related inking ribbon drum 35 therefore has imparted thereto one step of rotation in an inking ribbon winding-on direction, the inking ribbon unwinding from the other drum 35 because the latter drum is free to rotate 10 in an inking ribbon unwinding direction.

The operations are repeated in response to successive depressions of the key levers 5 and as a result the inking ribbon 60 is unwound step by step from one of the drums 35 onto the other of said drums. For each complete rotation of the gear wheel 34 associated with the winding-on drum 35 the related gear wheel 42 is advanced one step by the pin 37 of the related lever 36, and as a result of successive steps of rotation being imparted to said related gear wheel 42 the shaft 47 carrying the cams 48, 48a is gradually rotated until finally the positions of the cams 48, 48a are reversed, at a time, when substantially all of the inking ribbon 60 has become wound on one of the drums 35. Thereupon, the arm 27, that was held depressed, is permitted to rise and the other of said arms is depressed. The result is that subsequent actuations of the key levers 5 cause the inking ribbon to be unwound from the full drum 35 onto the empty drum 35. In this connection it is pointed out that the reduced speed gear trains between the gear wheels 34 and the shaft 47 are such in relationship to the length of the inking tape 60, that the cams 48, 48a are reversed at 35 times when the inking ribbon becomes substantially completely unwound from one of the drums 35 and substantially completely wound upon the other of said drums. Accordingly, as a result of operation of the machine, the inking ribbon 40 alternately is wound onto the respective drums 35, 35a.

It will be noted respecting the hammers 3c, that their arms 3b are disposed below the arms 3b of the hammers 3. Thus, the arms 3b of the hammers 3c are designed for cooperation with the lower portion of the ribbon 60, while the arms 3b of the hammers 3 are designed for cooperation with the upper portion of said ribbon. The upper and lower portions of the ribbon 60 may be 50 of different colors, black or blue and red, respectively, for example. Thus, the hammers 3 may produce characters of one color and the hammers 3c may produce characters of a different color. Usually, the hammers 3c are few 55 in number and carry punctuation marks.

Without further description it is thought that the features and advantages of the invention will be clearly understood. It is desired to point out, however, that while only a single structural embodiment of the invention has been illustrated and described, the invention is readily capable of embodiment in specifically different mechanical structures within its spirit and scope as defined in the appended claims.

65 I claim:

1. In a stenographic machine having an inking ribbon, a pair of drums on which the ends of said inking ribbon are wound, a pair of gear wheels one fixed to each drum, a pair of pinions

one related to each gear wheel, means whereby said pinions are reciprocated, means permitting rotation of each pinion in one direction and holding it against rotation in the opposite direction so that reciprocation of either pinion effects rotation of its related gear wheel and drum in only a single direction, a pair of rotatable cams one related to each pinion, a reduced speed train of gearing between each gear wheel and both of said cams, and means between each cam and its 10 related pinion effective to hold the related pinion in an inoperative position relative to its related gear wheel when the cam is in one position and to permit the related pinion to assume an operative position relative to its related gear wheel 15 when the cam is in another position, said cams being disposed diametrically opposite each other so that said pinions are rendered alternately operative and inoperative relative to their related gear wheel, thus to cause the inking ribbon alternately 20 to be wound onto the respective drums.

2. In a stenographic machine having an inking ribbon, a pair of drums on which the ends of said inking ribbon are wound, a pair of gear wheels one fixed to each drum, a pair of pinions one 25 related to each gear wheel, a pair of pivoted arms each carrying one of said pinions and each connected for reciprocation, thereby to reciprocate said pinions relative to their related gear wheels, means permitting rotation of each pinion in one 30 direction and holding it against rotation in the opposite direction so that reciprocation of either pinion effects rotation of its related gear wheel and drum in only a single direction, means tending constantly to swing said arms to dispose said 35 pinions operatively relative to their related gear wheels, a pair of rotatable cams of substantially semi-circular shape one related to each arm, a reduced speed train of gearing between each gear wheel and both of said cams, means between each 40 cam and its related arm effective to hold the arm in a swung position preventing cooperation of the related pinion with its related gear wheel when the cam is in one position and to permit swinging of said arm to a position in which its pinion may 45 cooperate with its related gear wheel when the cam is in another position, said cams being disposed diametrically opposite each other so that said pinions are rendered alternately operative and inoperative relative to their related gear 50 wheels, thus to cause the inking ribbon to be wound alternately onto the respective drums.

3. A stenographic machine as set forth in claim 2, in which the means between each cam and its related pinion carrying arm comprises a two-arm lever, one arm of which cooperates with the cam and the other with said pinion carrying arm.

4. A stenographic machine as set forth in claim 1, in which the reduced speed train of gearing between each gear wheel and the cams includes 60 a pair of members one related to each gear wheel and through which motion is transmitted from each gear wheel to said cams, and means mounting said members for rotation with said gear wheels in one direction and permitting rotation 65 of said gear wheels in the opposite direction relative to said members.

VICTOR CHARLES DOLD.
